ATTORNEYS.

UNITED STATES PATENT OFFICE.

DABNEY L. ERVIN, OF CRAWFORDSVILLE, MISSISSIPPI.

STOVE.

SPECIFICATION forming part of Letters Patent No. 225,812, dated March 23, 1880.

Application filed September 10, 1879.

To all whom it may concern:

Be it known that I, DABNEY L. ERVIN, of 5
Crawfordsville, in the county of Lowndes and
State of Mississippi, have invented a new and
Improved Stove, of which the following is a
specification.

Figure 1 is a plan of the stove with the top
removed on line $x x$, Fig. 2. Fig. 2 is a sec- 10
tional elevation on line $y y$, Fig. 1. Fig. 3 is
a plan of the soot-drawer. Fig. 4 is a sectional
end elevation of the front of the grate. Fig. 5
is a perspective view of a side plate, showing
the groove for a binding-rod; and Fig. 6 is a
perspective view of the grate. Fig. 7 is a sec- 15
tional detail view on line $z z$ of Fig. 3.

Similar letters of reference indicate corre-
sponding parts.

This invention consists in arranging the
binding-rods of the stove in vertical grooves
20 made in the edges of the side and back plates,
so that they (the rods) may be protected from
burning; in a peculiarly constructed soot-
drawer and scraper combined; in an ash-pan
secured in position in a novel manner, and in
25 a grate of peculiar construction, all of which
will be hereinafter described.

In the drawings, A represents the bottom
plate of the stove; B B, the top plates; C C,
30 the side plates; D, the back plate, and L the
front upper plate, the four latter of which, C,
C, D, and L, have grooved edges, as shown at
 a' , Fig. 5, in which grooves a' are laid the bind-
ing-rods b' , so that they (the rods b') may be
35 protected from intense heat, and may not in-
terfere with the cleaning of the stove, while
they permit the soot-drawer to extend from
side to side of the stove.

E represents the soot-drawer, that fits be-
tween the bottom A of the stove and the lower
40 cooking - shelf F, and extends backward far
enough to receive all the soot and ashes from
the back flues. This drawer E contains all the
under flues, E'', and can be withdrawn at any
45 time. It is provided with lugs c' , through
which rods or hooks pass to hold it in place,
and also with a swinging or other handle, d' ,
attached to its under surface.

Extending transversely across the central
part of the soot-drawer E, and secured at either
50 end in the sides $s' s'$ of the under flues, E'', is
a pin, f' , on which is pivoted the handle g' of

the scraper G. This handle g' extends out of
the front of the drawer E, and when the op-
erator pulls the drawer E out he may press
down upon the handle g' and force the scraper 55
G in contact with the under surface of the
lower shelf, F, so that it (the scraper G) will
remove therefrom all the accumulated soot
and ashes.

The flue-sides $s' s'$ are grooved on their up- 60
per surfaces, and extend upward in contact
with corresponding projections from the under
surface of the shelf F.

H is the ash-pan, which is held in place on
the hearth H'' by dovetailing the ends of the 65
raised rim h', the shape of the dovetailing be-
ing such that the front of the pan H must be
lifted from corresponding dovetails in the
hearth H'', in order that it may be withdrawn
at any time. 70

The grate M is composed, as herein shown,
of several pieces, which number can be in-
creased or diminished as circumstances may
require.

The ends of the upright bars $i' i'$ are dove- 75
tailed two ways, the one way to prevent them
from falling forward, and the other to prevent
them from being pulled out vertically, and
these bars $i' i'$ are tenoned into an upper and
lower horizontal bar, I and K, respectively, 80
whose ends are provided with sloping grooves
 k' and connected by two upright strips, l' ,
and rods m' . By pushing these strips $l' l'$,
which have beveled ends, rearward, the hori- 85
zontal bars I and K are forced apart, with
the effect of tightening the grate-bars $i' i'$
in their positions. The rods m' serve to hold
the strips l' in position. If the rods $m' m'$ be
removed, the grate M can easily be taken to 90
pieces and any broken or burned bars re-
placed.

The horizontal grate-bars $n' n'$ are dovetailed
in the same manner into their bearers K T.
The grate is prevented from swinging forward
or backward, is held in position by properly- 95
placed studs or stops, and is suspended from
the lugs o' , that are fixed on the inside of the
side plates, C C.

Many stove-grates become useless, or nearly
so, when a bar becomes broken, and must be 100
replaced by an entirely new one, while in this
grate M a single bar may be substituted for

any broken one, thus making this one the more economical of the two; and this grate can be readily applied to the cooking-stoves now in use without any alteration of the stove; 5 and the ash-pan and soot-drawer can be slightly modified to fit any ordinary cooking-stove.

Having thus described my invention, what I claim as new, and desire to secure by Letters Patent, is—

1. The plates C, C, D, and L, with grooved edges a' , for the reception and protection of the binding-rods $b' b'$, substantially as herein shown and described.

2. The scraper G, arranged in the soot-drawer and provided with a handle, g' , pivoted thereto at f' and extending to the outside, whereby either the top or the bottom of the flues may be scraped on operating the drawer, as shown and described. 15

3. The ash-pan H, provided with a dove-tailed front trim, substantially as herein shown and described. 20

DABNEY LIPSCOMB ERVIN.
